TORPEDO CARRIER AND DISCHARGER

Jesse D. Langdon, Downey, Calif.

Application January 20, 1942, Serial No. 427,397

7 Claims. (Cl. 114—17)

My present invention relates to torpedo carriers and dischargers, and more particularly to a torpedo carrier and discharger of the submersible dirigible type.

My invention is directed particularly to a torpedo carrier designed to be controlled and operated by one or more men and is designed to be submersible and to be equipped with all the necessary apparatus for its propulsion either above or beneath the water, and for the firing and sighting of torpedoes carried thereby.

In carrying out my invention I provide a torpedo carrier in the form of a hull made up of the necessary structural elements, but preferably having as a skeleton inner body, a frame formed of a plurality of longitudinal extending rigid members between adjacent pairs of which is stretched a flexible resilient or elastic skin made, for example, of rubber or rubberized fabric. When the torpedo carrier is resting on the surface or only slightly beneath the surface of the water, the flexible or elastic skin is inflated to such a degree as to enable the carrier to float on the surface and to present a full line appearance; the inflated skin serves as a cushion against damage to the carrier by depth charges or the like and minimize danger of collapsing of any hollow metal or other container of the carrier when the carrier has been submerged, the resilient or elastic material being flexed inwardly by concussion, thereby protecting the entire structure from damage.

My improved torpedo carrier is primarily designed for carrying one or two torpedoes, and as the torpedo carrier is relatively small, and as, compared to the torpedo carrier, the torpedo is relatively large, it is apparent that the discharge of the torpedo will seriously upset the balance of the torpedo carrier. I have, therefore, arranged balancing means for "trimming" the ship after the discharge of the torpedo so as to keep the torpedo carrier on an even keel, regardless of the presence or absence of the torpedo.

In the accompanying drawings:

Fig. 1 is a central, vertical, longitudinal section through one form of a torpedo carrier embodying my invention.

Fig. 2 is a vertical, sectional end elevation taken on the line 2—2 of Fig. 1.

Fig. 3 is a vertical, sectional elevation taken on the line 3—3 of Fig. 1.

Fig. 4 is a view of a modification of my invention.

Fig. 5 is a vertical, sectional elevation taken on the line 5—5 of Fig. 4.

Fig. 6 is a profile view of a preferred form of the invention, and

Fig. 7 is a transverse section of Fig. 6 at 7—7.

Referring to the drawings, and more particularly to Figs. 1 to 3, inclusive, 10 designates a plurality of substantially U-shaped members of steel or other rigid material, extending longitudinally as shown in Fig. 3, and being connected at their forward ends to a nose 11 and at their rear to a stern block 12. The form generally outlined by the members 10 is an elongated cigar-shaped skeleton or body between which are flexible and resilient plates 13. The longitudinal edges of the plates are inturned and housed within the U-shaped members 10 as shown in cross section in Figs. 2 and 3. The lowermost member 10 is located at the bottom of the vessel and inserted into the U-shaped member 10 at the bottom is a keel 14 for affording stability to the vessel.

Within the confines of the vessel is all of the mechanism and machinery for operating the same, as well as compartments for such mechanism, together with a torpedo tube or tubes for housing one or more torpedoes and a control compartment. Referring to Fig. 2, it will be noted that extending across the width of the body and secured to the upper longitudinal members 10 is a deck or platform 15 and that such deck or platform forms the deck of a control cabin or cage 16. The vessel is provided with a hatch 17 having transparent panels 18 therein, through which an observer seated within the control cabin 16 may look forward and to either side of the vessel to observe the course thereof. Within convenient reach of the operator's position is provided the usual telescoping periscope 19 for use when the vessel is submerged. Within the cabin 16 and rearwardly of the operator's position therein is arranged a storage cabinet 20 provided with doors 21 for the storage of food, medicine, etc.

Resting on the deck 15 and rearwardly of the supply cabinet 20 is arranged a high pressure air tank 22. Within the deck 15 and secured to the underside of such deck by hangers 23 is a torpedo tube 24. The forward end of the torpedo tube 24 extends through the nose 11 and has formed integral therewith at its forward end an annular flange 25 which is secured to the front face of the nose 11 and a passage 26 of a diameter equal to the diameter of a torpedo but less than the internal diameter of the torpedo tube 24. Within the torpedo tube 24 which acts as an elongated cylinder is slidably mounted a piston 27 provided on its front face with a toggle

immediately below the deck 15 and secured to the underside of such deck by hangers 23 is a torpedo tube 24. The forward end of the torpedo tube 24 extends through the nose 11 and has formed integral therewith at its forward end an annular flange 25 which is secured to the front face of the nose 11 and a passage 26 of a diameter equal to the diameter of a torpedo but less than the internal diameter of the torpedo tube 24. Within the torpedo tube 24 which acts as an elongated cylinder is slidably mounted a piston 27 provided on its front face with a toggle

clutch member 28 and having attached to its rear face one end of a cable (preferably steel) 29, which cable is slidably in a gland 30 in the end 31 of the torpedo tube 24.

The cable 29 is attached, one end to the reel or winch 31 and the other end to the rear face of the piston 27. The reel 31 is secured to a shaft 32 rotatably mounted in side frame members 33, see Fig. 3. These side frame members are shown mounted on top of an air pressure tank 34, secured in position on the frame members 19 or otherwise supported from movement. Secured to one end of the shaft 32 is a gear 35 which meshes with and is driven by a similar beveled pinion 40 secured to a propeller drive shaft 41 suitably mounted in bearings 42, and driven by the diesel motor or equivalent as set forth more fully hereinafter.

The interior of the torpedo tube 24 is in communication with the interior of the high pressure tank 22 through the conduit 42. In the conduit 42 is arranged a control valve 43 by means of which the connection between the high pressure tank 22 and torpedo tube 24 may be controlled at will. Mounted within the torpedo tube 24 is the torpedo 44 provided at its front end with the releasable war-head 45 and at its rear with the rudder 46 and propellers 47. The propellers are mounted on the propeller shaft 48 and on such propeller shaft is mounted the member 49 which cooperates with the toggle clutch members 28 that are mounted on the piston 27.

On the bottom of the torpedo carrier substantially amidships and on the platform 50 is mounted a prime mover 51 as a Diesel engine which is provided with a drive shaft 52 that may be directly connected to the drive shaft of an air compressor 53. The air compressor 53 is connected to the high pressure tank 22 through conduit 54 and to the pressure tank 34 through conduit 55. The conduit 55 has mounted thereon a control valve 56 to enable the operator to shut off the compressor 53 from the tank 34. A similar valve may be inserted in the conduit 54, though I have not shown such, as it is ordinarily not necessary. Mounted on the drive shaft 52 of the Diesel engine 51 is a beveled pinion 57 which meshes with and drives a corresponding beveled pinion 58 secured to the lower end of a shaft 59. The upper end of the shaft 59 is rotatably mounted in a bearing in the lower part of a clutch box 60. Also rotatably mounted on the clutch box 60 is the lower end of a shaft 61 which has secured to its top end a beveled pinion 62 which meshes with and drives the propeller shaft 41 which is provided on its front end with the beveled pinion 63. Associated with the clutch box 60 is the clutch lever 64 by means of which the power from the Diesel engine 51 may be utilized to drive the propeller shaft 41 or render the same idle.

The anterior propeller shaft 41 terminates at a clutching device (not shown) but located within the air turbine casing 65. As part of the clutch mechanism referred to but not shown is a member to which is secured the forward end of the shaft 66 and which shaft passes through a stuffing box 67 at the rear end of the hull and has secured to its after end the propeller 68. Pivotal mounted on the aft end of the hull is a rudder 69 which may be controlled from the operator's compartment 16 in any suitable or desired manner.

Within the turbine casing 65 is the usual tur-

bine operated by air under high pressure from the high pressure tank 22 which is conveyed to the rotor of the turbine through the conduit 70, a valve 71 controlling the flow of air and in turn operable from the operator's compartment 16. Mechanism not shown connects the rotor of the turbine within the casing 65 through the stated clutching device with the posterior propeller shaft 66.

As is usual, when the vessel is on the surface of the water, the turbine is out of commission and the propeller 68 is rotated from power generated from the Diesel engine 51. Simultaneously therewith the Diesel engine 51 operates the compressor 53 to maintain the high pressure tank 22 charged and also the tank 34 charged. When the vessel is under water and the Diesel engine can no longer be run with safety, the Diesel engine is placed out of commission and the propeller 68 is rotated by the turbine within the casing 65 from power derived from the air under pressure within the high pressure tank 22.

Assuming that the torpedo carrier is to pass through the operation of taking on a torpedo, air will be forced into the torpedo tube 24 to move the piston 27 therein outwardly until such piston abuts the flange 25. Because of the difference in diameter between the opening 26 and the flange 25 and the outer diameter of the piston which is the same diameter as the inside of the torpedo tube 24, the piston 27 will be stopped at this point. A torpedo 44 will now be backed up manually until the member 49 carried by the tail shaft 48 thereof will come into engagement with the toggle clutch 28. When this occurs, the operator, by throwing the clutch 38 see Fig. 3, will cause the reel 31 to be rotated to wind up the cable 29 thereon and draw the torpedo 44 into the torpedo tube 24 until such torpedo assumes its position within the torpedo tube shown in Fig. 1.

When it is desired to discharge the torpedo, the operator will open the valve 43 thereby permitting air under pressure to flow into the torpedo tube 24 behind the piston 27, forcing the torpedo 44 outwardly and simultaneously opening the toggle arms 28 so as to free the torpedo 44 from the piston 27.

In the status succeeding the discharge of a torpedo from the torpedo tube 24 and the piston 27 has been moved to the discharge end of the torpedo tube, the torpedo tube and its piston 27 may be employed for effecting rapid submerging of the torpedo carrier, namely, as a means for drawing water into the torpedo tube 24, which operation requires that the discharge end of the torpedo tube be under the surface of the water, a factor of high strategical value. In general, the torpedo tube 24, in the absence of carrying the torpedo, may be employed as a water container to such extent of its volume as may be desired by corresponding movement of its piston within the torpedo tube, for trimming the ship.

Referring now to Figs. 4 and 5, which show another embodiment of my invention, 80, 81 and 82 designate bottom frame members arranged parallel to each other and extending transversely of the hull 83. To the bottom frame members 80, 81 and 82 is secured a bottom plate or plates 84, forming thereby a flat floor for the bottom of the hull 83. Also, by reason of the arrangement of the members 80, 81 and 82, there is provided in the bottom 84 a plurality of steps 85 and 86, thereby providing a hydroplane bottom

formation for the hull 83. Arranged parallel with the bottom and spaced above and parallel to the bottom are longitudinals 87 and between the longitudinals 87 and the outer lateral edges of the members 80, 81 and 82 is stretched the side plating 88 of resilient material, such as rubber. Extending between the members 87 and arranged substantially parallel to the bottom 84 of the hull is a deck 89 which defines in association with the bottom 84 and side plating 88 a hold or compartment, or series of compartments, in which is housed the operative machinery for the device. The deck 89 is enclosed throughout its entire width and length by a hood or covering 90, and which in association with the deck 89 defines a chamber in which is located a control room together with various tanks for holding particularly air under pressure. The control room is located at the forward end of the deck 89 and is designated by the reference numeral 91. At the rear of the hull 83 is arranged the usual rudder 92 and the propeller 93 which is mounted on a shaft 94 extending through a gland at the rear of the hull 83, and having its forward end mounted in a bearing 95 and provided with a gear 96.

In the lower end of the hull 93 is arranged a torpedo tube 97 in which is slidably mounted a piston 98 having attached to its forward end a toggle clutch member 99 and having attached to its rear one end of a cable 100 which is mounted on a reel 101. Ordinarily mounted within the torpedo tube 97 is a torpedo 102 provided with the usual rudders 103 and propellers 104, and the propeller shaft of such torpedo is provided with a device 105 which is associated with the toggle clutch members 99 on the piston 98. When the torpedo 102 is in position, the nose 106 of the war-head thereof may project slightly beyond the hull 83 and I have arranged therefor a gasket 107 of resilient material which will maintain a water-tight joint between the war-head and the hull 83.

Mounted on the top of the cross frame members 80 and 81 is a platform 108 provided with a slideway 109 extending longitudinally of the platform and parallel with the length of the hull 83. On the platform is a prime mover such as a Diesel engine 110 and a compressor 111. The engine 110 is directly connected through its driving shaft 112 to the compressor 111 and the compressor 111 is connected to but slidably longitudinally with respect to a hollow shaft 113 rotatably mounted in a hanger bearing 114 depending from the under side of the deck 89. Also, the engine 110 and compressor 111 are rigidly connected together by spacing rods 115. Mounted on the after end of the platform 108 is a cylinder 116 closed at both ends by cylinder heads (not shown) and in one of such cylinder heads is an opening in which is slidably mounted a piston rod 117, the forward end of which is attached to the rear end of the base of the compressor 111 and the rear end of which is attached to a piston (not shown) slidably mounted within the cylinder 116. Mechanism of the usual type is arranged under the control of an operator within the operating compartment 91 for passing air under pressure to either side of the piston within the cylinder 116 at will, to thereby render it possible for the operator in the control compartment 91 to move, as a unit, the engine 110 and compressor 111 longitudinally in either direction on the slideway 109 on the upper surface of the platform 108. This mechanism is essential

because of the small size of the entire apparatus and the unbalancing which must necessarily occur when a torpedo 107 is either discharged from the torpedo tube 97 or drawn into such tube. The operator under such circumstances therefore in order to maintain the hull 83 in balance will move the engine 110 and compressor 111 either forward or aft of the hull in order to maintain the hull in balance.

Secured to the shaft 113 is the forward end of a shaft 118, which is rotatably mounted in a bearing formed in the cross frame member 82. This shaft 118 is provided adjacent the hanger bearing 114 with a beveled pinion 119 which meshes with and drives a beveled gear 120, mounted at the top of a shaft 121, and by means of which power is transmitted to the reel 101, the power being imparted to the reel 101 so as to rotate the same at will to draw the piston 98 by means of the cable 100 rearwardly when it is desired to draw a torpedo 102 into the torpedo tube 97.

At the rear end of the shaft 118 is a gear 121, which meshes with and drives a gear 122 attached to the rotor shaft of an air turbine 123, and which shaft has at its rear end a gear 124, which meshes with and drives the gear 96 attached to the forward end of the posterior propeller shaft 94. Because of the usual and known construction, and as explained in connection with Figs. 1, 2 and 3, the various tanks for compressed air and the various control valves for the different mechanisms above described have not been shown in further detail in connection with Figs. 3, 4 and 5. This omission is for the sake of simplicity of showing and description, and it is believed that the method of operation of the various devices by control devices located within convenient reach of the operator within the control compartment 91 will be readily understood from the hereinabove description of the construction shown in Figs. 1, 2 and 3.

It is understood also that in connection with Figs. 1, 2 and 3, there is provided naturally diving vanes for inducing an upward and downward motion of the hulls in the water, in addition to the steering mechanism 92. Such a construction is shown in Figs. 4 and 5 where 125 designates a shaft mounted in suitable bearings 126 in the shell of the hull, and having attached to its outer ends and without the hull the diving vanes 127. Secured to the shaft 125 intermediate its ends is a worm wheel 128 with which meshes a worm 129 attached to the lower end of a column or shaft 130, such shaft being provided at its upper end with a wheel 131 within convenient reach of an operator within the control compartment 91. Such a mechanism as described in Figs. 4 and 5 will of necessity be provided in the construction shown in Figs. 1, 2 and 3, but, for simplicity of showing, such mechanism has been omitted in such Figs. 1, 2 and 3.

Figs. 6 and 7 show a preferred form of the hull wherein the structure comprises a substantially cigar-shaped metal body 90b which is the full equivalent of the irregular metal body portion designated by numerals 90 as of the other forms shown in Figs. 1 to 5.

The body 90b is partially surrounded by the flexible casing 13-88 which is the equivalent of panelled casing 13 of Figs. 1 to 3 and flexible panels 88 of Figs. 4 and 5.

The ballonets 150 are arranged within the casing 13-88 partially surrounding the cigar-shaped

body 90b and are inflated in the same manner as described to inflate the compartments within the flexible panels 13 of Figs. 1 to 3 and panels 88 of Figs. 4 and 5. The other elements embodied within the other forms of hull shown by Figs. 1; 2, 3, 4 and 5 are identical and designed to be arranged in the same relative positions as of the other forms of the invention in order to balance and trim the hull.

The outer flexible casing 13-88 is forced and held to form by inflating balloonets 150. In case of the puncturing of one or more of the balloonets 150, the other balloonets are designed to enlarge automatically to fill the space due to the collapse of the other balloonets.

In order to submerge the form shown in Figs. 6 and 7, the air or gas is withdrawn from the balloonets 150 in the same manner as described to collapse the panels 13 as of Figs. 1-3 and 88 as of Figs. 4 and 5.

Whereas I have described my invention by reference to specific forms thereof, it will be understood that many changes and modifications may be made without departing from the spirit of the invention.

I claim:

1. A submersible vessel combining an inner hull comprising a supporting frame, an outer flexible hull substantially surrounding said inner hull and made of material flexible enough to deform and capable of assuming original form after being deformed, said outer hull subject to being inflated for surface navigation and deflated to submerge the vessel, and balloonets encased within said outer flexible hull and capable of holding said outer flexible hull to form.

2. A submersible vessel comprising a rigid framework of mutually spaced structural members defining a skeleton frame, flexible, impervious sheet material secured to and extending between successive structural members to provide

flexible side-plating enclosing the vessel; a rigid deck internally of said vessel to subdivide the same, air compressor means for generating gaseous pressure within the hull to permit the said flexible side plating to be expended against the water pressure externally of said hull or partially collapsed by said water pressure according to the buoyancy requirements of said hull, and drive means for said air compressor.

3. A vessel according to claim 2, in which the compressor means may be shifted laterally of said hull to trim the vessel.

4. A vessel according to claim 2 in which the compressor means and drive means therefor are 15 articulated and may be collectively shifted within the hull to adjust the center of gravity thereof.

5. A vessel including a skeleton frame of rigid structural members joined at their front ends to a common rigid nosepiece and at their opposite 20 ends to a common rigid stempiece, a flexible hull plating comprising resilient flexible sheet material secured to said structural members, and means for controlling the cubical content of said hull by gaseous pressure generated within said 25 hull to expand said flexible hull or to permit the controlled collapse thereof under the water pressure externally of said hull.

6. A vessel according to claim 5, in which the vessel includes a torpedo tube, means for discharging the torpedo, and means for introducing water into the torpedo tube for compensating for the weight of the discharged torpedo to trim the vessel.

7. A vessel comprising a rigid framework defining an inner hull, an outer plate, of flexible, material secured to and extending around said inner hull, inflatable means disposed between said inner hull and said flexible outer plating, and means within the vessel for controlling the inflation of said inflatable means.

JESSE D. LANGDON.
